UNITED STATES PATENT OFFICE.

HARRY WEARNE, OF NEW YORK, N. Y.

DESIGN FOR A PRINTED FABRIC OR SIMILAR ARTICLE OF MANUFACTURE HAVING SURFACE ORNAMENTATION.

56,683.

Specification for Design.

Patented Nov. 23, 1920.

Application filed May 27, 1920. Serial No. 384,739. Term of patent 7 years.

To all whom it may concern:

Be it known that I, HARRY WEARNE, a subject of Great Britain, and resident of the borough of Manhattan, in the county, city, and State of New York, have invented a new, original, and ornamental Design for Printed Fabrics and Similar Articles of Manufacture Having Surface Ornamentation, of which the following is a specification, reference being had to the accompanying drawing, forming a part thereof.

In the said drawing:—

The figure is a plan view of a portion of a printed fabric showing an embodiment of my new design, which is also applicable to

paper and composite materials in sheet form.

I claim:

The ornamental design for a printed fabric or similar article of manufacture having surface ornamentation substantially as shown and described.

In testimony whereof I have signed my name to this specification in the presence of two subscribing witnesses.

HARRY WEARNE.
